CHARLES W. KECKLER, OF NEWARK, NEW JERSEY, ASSIGNOR, BY MESNE ASSIGNMENTS, TO WESTERN ELECTRIC COMPANY, INCORPORATED, A CORPORATION OF NEW YORK.

SERVICE-OBSERVING CIRCUIT FOR TELEPHONE-LINES.

1,272,673.

Specification of Letters Patent. Patented July 16, 1918.

Application filed April 14, 1915. Serial No. 21,251.

To all whom it may concern:

Be it known that I, CHARLES W. KECKLER, a citizen of the United States, residing at Newark, in the county of Essex and State of New Jersey, have invented certain new and useful Improvements in Service-Observing Circuits for Telephone-Lines, of which the following is a full, clear, concise, and exact description.

0 This invention relates to telephone exchange systems, and more particularly to a service observing circuit adapted to be associated with a subscriber's line.

Heretofore service observing circuits have been provided in exchanges where a main and intermediate distributing frame are used. The object of this invention is to provide a service observing circuit adapted to be used in exchanges where only a main distributing frame is available.

In accordance with this invention there is provided a service observing circuit adapted to be connected with the talking conductors of a subscriber's line. This circuit is inserted in a subscriber's line circuit at some point intermediate the main distributing frame and the line jack in which said subscriber's line terminates. Included in the observing circuit are a plurality of indicating devices, one of said devices being adapted to be actuated whenever a call is initiated upon a subscriber's line with which said circuit has been associated, and another of said devices being adapted to be actuated whenever a call is received upon said line. Through the medium of these indicating devices an observing operator will be informed as to the class of service rendered a given subscriber, the time required to render said service, etc.

This invention is illustrated in the accompanying drawing in which Figure 1 shows an arrangement of apparatus wired in accordance with this invention, and Fig. 2 is a modification of part of the circuit shown in Fig. 1.

A subscriber's substation is connected by means of line wires 1, 2 to a line jack 3 located at a central office. Associated with the line circuit is a line relay 4 and a cutoff relay 5, the former being adapted to be energized upon the removal of the receiver from the switchhook at the substation and the latter being energized when the operator in-

serts an answering plug 6 into the line jack 3. The line relay 4 controls a line lamp 7 in the usual manner. A service observing circuit 8 is adapted to be associated with the circuit of the substation, said observing circuit being preferably connected with said line circuit at the main frame. The apparatus comprising the observing circuit 8 is located on a special board having a special attendant for the purpose of observing the performance and efficiency of any given operator. The equipment included in the observing circuit is adapted to serve only one line at a time; consequently where it is necessary to render special service to several subscribers simultaneously, several of these circuits must be supplied.

The operation of the apparatus shown in the drawing is as follows: When a subscriber at the substation removes his receiver from the hook, in addition to effecting the energization of the line relay 4 the following circuit is established: source of current 9, winding 10 of relay 4, conductor 11, contact 12, conductor 14, line wire 2, through the substation and return by way of line wire 1, conductor 15, contacts 16, 17 winding of relay 18 to ground. Simultaneously with the completion of this circuit just traced, the following circuit is established through the relay 19: battery 9, coil 10 of relay 4, conductor 11, contact 12, conductor 14, line wire 2, through the substation and back, line wire 1, conductor 15, winding of relay 19, conductor 20, contact 21, winding 22 of relay 19 to ground. It may be mentioned here that the relay 19 is of the marginal type and does not respond at this time.

The energization of the relay 18, brought about by the closure of the circuit traced above, closes its contact 25, thus establishing a circuit for a signal or lamp 26, which may be traced as follows: battery 27, lamp 26, contact 25 to ground. The lamp 26 will remain lighted until an operator inserts the answering plug 6 into the line jack 3 in response to the actuation of the line lamp 7 associated with the calling line. Upon the insertion of the plug 6 into the jack 3, current of sufficient strength is supplied to actuate the relay 19 over the following circuit: battery 28, conductor 29, contact 30 of the ringing key 31, sleeve side of the plug 6 and jack 3, conductor 20, winding of relay 19,

- conductor 15, line wire 1, through the substation and return by way of line wire 2, conductor 14, tip of the jack 3 and plug 6, contact 33 to the other side of battery 28. The relay 19 in pulling up its armature opens contact 17, thus interrupting the circuit through the relay 18, which in turn effects the effacement of the lamp 26. When it is desired to call the particular number assigned to the substation under consideration, upon the application of ringing current to the subscriber's line by the actuation of the ringing key 31, in addition to ringing the bells at the substation the following circuit is completed through the relay 32, source of generator 34, contact 35, sleeve of the plug 6 and jack 3, conductors 20, 36, winding 37 of relay 32, through the condenser 38, conductor 14, tip of the jack 3 and plug 6, contact 39 to ground. The relay 32 is adapted to be energized by alternating current, and in pulling up forms a locking circuit for itself which may be traced as follows: battery 41, winding 40 of relay 32, contact 42, conductor 43, contact 44 of the operator's listening key 45, to ground. The closure of this circuit effects the establishment of a circuit through the lamp 47 over the following path: battery 27, lamp 47, conductor 48, coil of relay 46, conductor 49, contact 42, conductor 43, contact 44 to ground. The closure of this circuit lights the lamp 47 and causes the energization of the relay 46 which in pulling up its armature opens the contact 16 and closes contact 23, thus shunting the relay 19 out of the ringing circuit, thereby creating a low-resistance path for the ringing current applied to the subscriber's line. The relay 32 will remain energized until the listening key 45 has been operated in a manner to open contact 44.

Fig. 2 shows a modification of the arrangement of the apparatus comprising the observing circuit shown in Fig. 1. In place of providing a locking circuit for the relay 32 as disclosed in Fig. 1, this feature may be omitted as illustrated in Fig. 2. According to the circuit connection shown in Fig. 2, the relay 32 will be energized during the period ringing current is applied to the line, and in event machine ringing current is used, said relay will be energized and de-energized periodically in synchronism with the application of ringing current to the line. The energization and deenergization of the relay 32 will flash the lamp 47 as the circuit through said lamp is closed and opened by the actuation of the relay 32. By this arrangement, it is obvious that the observing operator will be relieved of the necessity of operating her listening key 45, to restore the relay 32 to normal position, whenever the subscriber's line under observation was called; and at the same time, due

to the flashing of the lamp 47, she would be informed of the interval of time during which ringing current was applied to the called line.

From the above it will be apparent that in cases where special attention is desired to be paid to certain subscribers' lines by the means provided in this invention, a check may be obtained upon the service rendered in establishing connections with incoming and outgoing calls to a given substation.

What is claimed is:

1. In a telephone system, a line circuit terminating at a central office, a service observing circuit connected with the talking conductors of the line circuit, a signaling device therefor controlled over the line circuit and operated upon the removal of the receiver from the switchhook to furnish a signal, a connecting circuit at the central office, and a relay in circuit with the talking conductors of the line circuit rendered effective by the connection of the connecting circuit with the line circuit to cause the effacement of the signal.
2. In a telephone system, a line circuit terminating in a line jack at a central office, lamp 47 over the following path: battery 27, a service observing circuit adapted to be connected with the talking conductors of said line circuit, a signaling device included in said service observing circuit, a relay adapted to be energized over said line circuit by the removal of the receiver from the switchhook for effecting the operation of said signaling device, a connecting circuit at the exchange, and a relay in series with said line conductors which becomes operative upon connection of said connecting circuit with said line conductors for effacing said signal.
3. In a telephone system, a line circuit extending from a subscriber's station to and terminating at a central office, a line signal observing circuit for the telephone line, a service observing signal for the line, a relay energized upon the removal of the receiver from the switchhook for causing the operation of the service observing signal, a relay for causing the effacement of the service observing signal, a line relay controlling the line signal, an energizing circuit for the line relay established upon the removal of the receiver from the switchhook and including the winding of the second-mentioned relay, a link circuit for extending the telephone line, and an energizing circuit for the second-mentioned relay established upon the connection of the link circuit with the telephone line.

4. In a telephone system, a line circuit terminating at a central office, a service observing circuit connected with the talking conductors of the line circuit, a signaling device therefor, a relay in circuit with the talking conductors for controlling the signal, and a link circuit for extending the telephone line, and an energizing circuit for the second-mentioned relay established upon the connection of the link circuit with the telephone line.
5. In a telephone system, a line circuit terminating at a central office, a service observing circuit connected with the talking conductors of the line circuit, a signaling device therefor, a relay in circuit with the talking conductors for controlling the signal, and a link circuit for extending the telephone line, and an energizing circuit for the second-mentioned relay established upon the connection of the link circuit with the telephone line.

naling device, a source of ringing current, a relay bridged across the talking conductors and responsive to current from said source, a signaling device controlled thereby, a relay actuated upon the operation of the bridged relay for disabling the first-mentioned relay while ringing current is applied to the line.

5. In a telephone system, a line circuit extending from a subscriber's station to and terminating at a central office, a line signal for the line, a line relay controlling the line signal, a service observing signal, a first and a second relay controlling the service observing signal, an energizing circuit for the line relay established upon the removal of the receiver from the switchhook and including the winding of the second relay, an energizing circuit for the first relay established upon the removal of the receiver from the switchhook and including a normally closed contact controlled by the second relay, a link circuit for extending the telephone line, and an energizing circuit for the second relay established upon the connection of the link circuit with the telephone line, whereby the normally closed contact is opened.

6. In a telephone system, a line circuit extending from a subscriber's station to and terminating at a central office, a line signal for the line, a line relay controlling the line signal, a service observing signal, a first and a second relay controlling the service observing signal, an energizing circuit for the line relay established upon the removal of the receiver from the switchhook and including the winding of the second relay, an energizing circuit for the first relay established upon the removal of the receiver from the switchhook and including the normally closed contact of the second relay, a link circuit for extending the telephone line, and an energizing circuit for the second relay including contacts of the engaged link and line circuits.

7. In a telephone system, a line circuit extending from a subscriber's station to and

terminating at a central office, a line signal for the line, a line relay controlling the line signal, a service-observing signal, a first relay connected in series with the line circuit, a second relay connected with the line circuit through a normally closed contact of the first relay and coöperating therewith to control the service observing signal, an energizing circuit for the line relay established upon the removal of the receiver from the switchhook and including the winding of the first relay, an energizing circuit for the second relay established upon the removal of the receiver from the switchhook, a link circuit for extending the telephone line, and an energizing circuit for the first relay established upon the connection of the link circuit with the telephone line for disconnecting the second relay from the line.

8. In a telephone system, a line circuit extending from a subscriber's station to and terminating at a central office, a line signal for the line, a line relay controlling the line signal, a service observing signal, a first relay connected in series with the line circuit, a second relay connected with the line circuit through a normally closed contact of the first relay and coöperating therewith to control the service observing signal, an energizing circuit for the line relay established upon the removal of the receiver from the switchhook and including the winding of the first relay, an energizing circuit for the second relay established upon the removal of the receiver from the switchhook, a link circuit for extending the telephone line, an energizing circuit for the first relay established upon the connection of the link circuit with the telephone line, a source of ringing current, and a relay responsive to the connection of the ringing current with the telephone line for removing the first relay from the line circuit.

In witness whereof, I hereunto subscribe my name this 13th day of April A. D., 1915.

CHARLES W. KECKLER .
